UNITED STATES PATENT OFFICE

2,498,943

ILLUMINATED SWITCH SOCKET

Joseph F. Courtney, Chicago, Ill.

Application April 21, 1947, Serial No. 742,933

10 Claims. (Cl. 240—2)

1

The present invention relates to illuminated switch sockets, and is particularly concerned with the provision of an improved socket of the switch type which is adapted to be illuminated in the dark when the light is turned off, so that the lamp installation may be found in the dark without difficulty.

One of the objects of the invention is the provision of an improved lamp socket of the switch type, a portion of which is adapted to be illuminated by means of a glow lamp whenever the switch is in the "off" position, and which also gives a positive indication whether the lamp is burned out.

Another object of the invention is the provision of an improved electric switch socket for electric bulbs which is provided with a suitable source of illumination, preferably of the type comprising a glow lamp with spaced electrodes, which uses such a small amount of electric current that the expense of its operation for many thousand hours may be negligible, and which has such high efficiency that it may be used for many thousand hours without replacement.

Another object of the invention is the provision of an improved electric switch socket structure of the class described having a source of illumination within the socket, which can be manufactured at a very low cost, so that it may be placed within the reach of a large number of the public, and the structure of which is very simple, so that its assembly or replacement involves a minimum amount of labor.

Another object of the invention is the provision of an improved housing member for electric switch sockets and the like which may be constructed in various useful embodiments in which the housing member may be transparent, translucent, opaque with windows, or it may be translucent and provided in different colors, such as green or red or amber, as required in the different installations, for example, at home, commercial, industrial, traffic control, etc.

Another object of the invention is the provision of an improved electric switch socket structure including an illuminated housing in which the glow lamp used for illumination is suitably protected and insulated from the electric leads, and so housed that it is not apt to be damaged by persons using a screw-driver upon the connector screws or other parts, and the structure of which is sturdy and efficient, so that the assembly may be used for practically an indefinite period of time without necessity for repair or replacement.

Another object of the invention is the provision

2

of an improved illuminated housing for electric switch sockets in which the light emitted is suitably diffused, and in which there is a control of the brilliancy so as to avoid glare or excessive brilliancy.

Another object of the invention is the provision of an improved illuminated electric switch socket, the parts of which are so arranged that there is no possibility of short circuit between the electrodes of the lamp which illuminates the housing, and in which both the lamp and the resistance which is utilized with the glow lamp are suitably supported in such manner that no undue strains are placed upon either the lamp, its electrodes, or the resistance member.

Other objects and advantages of the invention will be apparent from the following description and the accompanying drawings, in which similar characters of reference indicate similar parts throughout the several views.

Referring to the single sheet of drawings,

Fig. 1 is an axial sectional view of an electric switch socket embodying the invention.

Fig. 2 is a wiring diagram showing the circuit of the device.

Fig. 3 is a fragmentary sectional view taken on the plane of the line 3—3 of Fig. 1 looking in the direction of the arrows.

Fig. 4 is a top plan view of the switch and lamp unit taken on the plane of the line 4—4 of Fig. 3.

Fig. 5 is a sectional view taken on the plane of the line 5—5 of Fig. 3.

Fig. 6 is a fragmentary elevational view in partial section of a modification in which the housing is provided with windows.

The socket assembly preferably includes the lamp and switch unit 10, which is shown in plan in Fig. 4, and the socket housing which consists of a tubular body member 11 and a light-transmitting cap 12 secured together by means of a threaded ring 13.

The tubular housing member 11 is preferably molded out of insulating material, such as a suitable plastic or a phenolic condensation compound, and it has a smaller portion 14 for housing the screw connector sleeve 15 and a larger portion 16 for housing the switch and lamp unit 10. These two tubular portions of different diameter are separated by an annular shoulder 17 against which the switch and lamp unit 10 may seat at its corners.

The smaller tubular portion 14 may have external threads 18 for the purpose of receiving the threaded rings which support lamp shades.

The larger tubular portion 16 is also provided at its upper end with external threads 18 which are complementary to the pressed threads 20 formed on the screw ring 13.

The screw ring 13 also has an inwardly extending radial flange 21 which engages on the outside of a portion of the cap 12, such as, for example, the annular surface 22, to press the cap 12 against the annular end seating surface 23 on the larger portion 16 of the sleeve.

At one side the sleeve portion 16 is provided with a slot 24 extending into its end surface 23, and the cap 12 is provided with an axial lug 25 or key for determining the radial position of the cap 12 upon the housing member 11.

The screw sleeve 13 may be made of various materials, such as a suitable plastic, but is preferably stamped out of thin sheet metal. The cap 12 preferably comprises a translucent or transparent integral plastic member which is adapted to transmit the illumination which is provided by a glow lamp 26 forming a part of the switch and lamp unit 10.

Various types of plastic may be employed, such as a polystyrene, and the plastic may be clear, translucent, or colored, depending upon the type of installation.

The cap 12 preferably has a semi-ball-shaped body 27 which is formed at its lower edge with an outwardly extending annular flange 28. The flange 28 engages under the screw ring 13 and permits the cap to be secured to the body 11.

At its upper end the cap 12 is preferably formed with a relatively thick tubular extension 29 having an enlarged and internally threaded bore 30 which is usually adapted to receive a threaded pipe through which the conductors pass, but the conductors 31, 32 may merely pass out of the threaded bore 30, or they may be provided with a suitable grommet, if desired.

The body of the cap 12 preferably increases in thickness toward the top, so that it is strong in construction and adapted to withstand abuse. The cap 12 is formed on its interior with a semi-ball-shaped cavity 33 within which are housed the conductors 31, 32, and the neon lamp 26 which provides the source of illumination.

The present invention may include various types of electric switch structures, but the assembly preferably includes a snap switch such as the one illustrated. Thus the switch comprises a pair of housing members 34, 35 of molded insulating material for housing and supporting the contacts and other switch elements. These two members are joined along the central plane 36 where they are provided with suitable complementary surfaces, and they are held together by means of a rivet 37 passing through the members 34, 35 and riveted over at its end at 38.

The rivet also supports and secures the screw sleeve 15 in place, and for this purpose the screw sleeve is provided with a pair of axially projecting tabs 39, 40, each being provided with an aperture for passing the rivet 37. The screw sleeve 15 may be of conventional construction, comprising a pressed sheet metal cylindrical member, the cylindrical body of which is shown at 41. At its upper end the tabs 39 and 40 are supported by an inwardly extending flange 42 which borders a cruciform opening.

The cylindrical body 41 of the screw sleeve 15 has its lower or end portion provided with helically formed pressed threads 43 which are complementary to the threads on the connector plug of an incandescent bulb.

The rivet 37 also supports and secures one of the connectors 44 to the side of the member 35. This connector 44 consists of a strip of sheet metal which is provided with a threaded bore 45 for receiving the screw bolt 46 which clamps the end of the conductor 32.

The insulating body member 34 preferably has a socket 47 for receiving the end of screw bolt 46 by means of which the connector strip 44 is prevented from rotating on the rivet 37.

Referring to Fig. 3, the insulating body 34 is provided with a centrally located, substantially rectangular chamber 48. Within this chamber there are located two fixed contacts 49 and 50 which are adapted to be bridged by means of a movable contact member 51 (Fig. 1). In order to provide proper connections for the lamp, the fixed contact 50 forms a part of a U-shaped spring member 52 of sheet metal, which fits in a slot 53.

The U-shaped spring member 52 has one of its legs 54 supporting the elongated contact 50. The other of its legs 55 is extended and enlarged, and supports the contact member 56 comprising a disk-like spring with an outward curved bulge for engaging the center contact of an incandescent bulb.

The body member 34 also supports the fixed contact 49 which is carried by a U-shaped metal member 57. In this case the shape of this U-shaped member 57 is best shown in Fig. 5. One of its legs 58 is arranged externally to the insulating members 34, 35. The yoke 59 of the U-shaped member 57 extends across the end of the insulating member 34. The other leg 60 of the U-shaped member 57 extends inwardly of the insulating member 34 and carries the upwardly extending contact 49 (Fig. 5).

When the blocks 34, 35 are assembled, the parts 40 of the block 35 which are arranged externally to the contacts 49 and 50 aid in holding these members in place, and the block 35 has slots for receiving the projecting portions of the U-shaped member 52 and the U-shaped member 57.

At its center bottom the chamber 48 has a cylindrical socket 61 for receiving the end of a helical coil spring 62. This coil spring is closely wrapped at its upper end portion 63 where it surrounds and is fixedly secured to the stem 64 of the moving contact 51. As seen in Fig. 1, the moving contact 51 is of substantially V-shape, with outwardly extending end portions 65 on each of its legs. These end portions are pressed to form the projecting contacting faces 66 which engage the contacts 49 and 50.

The movable switch contact member 51 is provided with an actuator 67. This actuator member consists of an elongated strip of metal, such as steel, each end of which bears a shank portion 68, 69 which is embedded and secured in a cylindrical insulating push-button member 70 or 71. One of the push-button members is preferably black in color, indicating darkness or the "off" switch position, while the other push-button member is preferably of a color which indicates illumination, such as red. Thus the push-button 70, which is pushed to close the switch, may be red, while push-button 71 may be black.

Each push-button has its end surface suitably curved at 72 for smooth engagement with the finger of a user.

Intermediate its ends the actuating member 67 is provided with two camming surfaces 73, 74 separated by a ridge or high point 75. The depth 75 of the ridge 75 and camming surfaces 73, 74 is

greater than the depth of the V-shaped slot 76 in the movable contact member 51, but the narrow stem portions 78 and 79 of the actuating member 57 have a clearance with respect to the base of the slot 76.

The insulating blocks 34 and 35 have complementary formations for slidably supporting the push-buttons 10, 11 and for slidably guiding the actuating member 67, such as the cylindrical sockets 17, 18 and the flat guide surfaces 19 and 20. Thus the actuating member 67 may be pushed back and forth, one of its positions being shown in Fig. 5 where the switch is open.

When the switch is to be closed, the button 11 is pressed, and the action is as follows: The camming surface 13 forces the V-shaped contact member 51 downwardly in Fig. 5 until the ridge 75 passes over the contact member 51. During this time the contact member 51 engages the side wall 81 of the chamber 48, but as soon as the ridge 75 passes over the contact member 51 the camming surface 14 is engaged by the contact member, and the actuating member 67 is then cammed toward the left, while the contact 51 slides upward on the camming surface 14 under the influence of spring 62, and the contact 51 snaps toward the right to engage fixed contacts 49 and 50, which it bridges.

The block 34 is provided with a bore 82 (Fig. 5) for receiving a resistor which is connected in series with the neon lamp to limit the amount of current. The cylindrical bore 82 receives and houses and protects the resistor 83 which has a conductor extending axially from each of its ends.

The resistor is seen in dotted lines at 83 extending upwardly and downwardly in Fig. 3. It is located so that it is insulated and spaced from all of the metallic switch parts in the block 34.

The wire 84 from one end of the resistor 83 is brought out of the block and extended under the U-shaped member 52, where it is soldered at 85 to this U-shaped member 52. Thus the resistor 83 is connected to the center contact of the screw socket 56 and also to the fixed contact 50.

The wire 86 from the other end of the resistor 83 (Fig. 3) extends upwardly through a suitable bore and is laterally turned and twisted into firm engagement with one of the leads 87 from the neon lamp 26. The two twisted conductors are shown at 88 and they are preferably covered with a short tube of rubber 89. The other lead 90 from the glow lamp 26 is soldered to the U-shaped member 57 at the point 91.

Thus the resistance 83 and the glow lamp 26 are in series, but they are bridged across the two open contacts 49 and 50. The glow lamp and its resistance are also in series with the lamp circuit, so that when the switch is open, the lamp circuit is nevertheless energized through the resistance 83 and glow lamp 26, but the resistance so limits the current that there is no illumination of the incandescent bulb, and only the glow lamp is illuminated on open circuit.

These circuit arrangements are best shown in Fig. 2, which is a circuit diagram. Here 83 indicates the resistance and 26 the glow lamp. The fixed contacts are again 49 and 50, and the bridging contact is 51. The incandescent bulb placed in the screw socket 43 is indicated at 92. It is connected in circuit by the two line conductors 31 and 32, one of which passes directly to the incandescent bulb 92, and the other of which passes to it only through the switch contacts or the glow lamp and its resistance.

The glow lamp 26 preferably lies against the

flat face 95 of the switch unit, where it is held by a complementary stirrup, guard or shield 96. This stirrup is shown in plan in Fig. 4 and in transverse section in Fig. 1. It comprises a central cylindrical portion 97 and a pair of flat attaching flanges 98 and 99.

The cylindrical portion 97 embraces and engages the cylindrical body of the glow lamp 26, which is frictionally held therein. The attaching flanges 98 and 99 are each provided with an aperture for receiving a headed friction pin 100. The pins 100 are driven through the flanges 98 and 99 into suitable bores 101 in the insulating members 34, 35, thus securing the stirrup or shield 96 in place, and also securing the glow lamp 26 to the switch unit.

Shield 96 is preferably made of a suitable plastic having insulating light-transmitting qualities, and it is preferably extended so that it overhangs the conductors 90 and 87 which come out of the end of the glow lamp 26. Thus the glow lamp is suitably insulated from the line conductors 31 and 32.

There is no possibility that loose strands of the twisted electrical conductors 31 and 32 may come into engagement with parts of the lamp. The lamp is also protected against engagement with a screwdriver or other tool which may be used by the operator on the connector screws 46.

Referring to Fig. 6, this is a fragmentary sectional view similar to Fig. 1, showing an alternative form of cap 12a which might be made of metal, but which is preferably provided with a plurality of window openings 102. Such a metal cap may be opaque, but may have under it a pressed plastic dome adapted to transmit light through the windows 102, and to prevent users from pushing anything into the socket.

The plastic dome 103 is partially ball-shaped, and fits inside the cap 12a. It has a radially projecting securing flange 104 which is clamped between the cap 12a and the end surface 23 of the housing 11. Such a dome may be made of clear light-transmitting material; it may be transparent, translucent, or made of various colors, such as green, red, or amber, depending upon the effect desired. A socket used for a fire exit light would thus be provided with a red dome 103 through which the illumination from the neon lamp 26 would be colored red.

The operation of my illuminated switch socket is as follows: When the switch is closed the glow lamp 26 and its resistance are short-circuited by the closure of the switch contacts, and the glow lamp is extinguished. Such is the case when the incandescent bulb 92 is being burned.

When the switch is opened, the circuit is opened at 49, 51, 50, and the incandescent bulb is extinguished. The incandescent bulb 92 is still connected in circuit through the glow lamp 26 and resistance 83, but the amount of current passing through it is so minute that it is almost immeasurable, and, of course, is not sufficient to illuminate the incandescent bulb.

On open circuit the glow lamp 26 is illuminated, and the illumination in the top of the socket causes the cap 12 to glow with sufficient light so that the switch can be found in the dark.

It is well known that such electric switch sockets are usually employed at points where there are no wall sockets, and thus they must be found by the user in the dark, but with the present invention the socket will always be illu-

minated when its incandescent bulb is extinguished. Thus the user can find the switch at any time.

It will thus be observed that I have invented an improved illuminated switch socket for incandescent bulbs. My socket is illuminated only when the bulb is extinguished, and the illumination is visible only when the room is dark, as that is the time when the illumination is needed. Although the glow lamp burns continuously, it 10 employs so little current that it is negligible.

The present invention embodies the glow lamp and its necessary resistance in a switch unit in such manner that all of its parts are suitably protected and insulated. The structure is simple, capable of economical manufacture and sale, and adapted to be used for a long period of time without necessity for replacement or repair of any of its parts.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In an illuminated electrical switch socket, the combination of a housing member with a switch unit in said housing member and an electrical connector carried by said housing member for receiving an incandescent bulb, said switch unit controlling the line connection to said electrical connector, and a source of illumination located inside said housing and visible on the outside of said housing, said source being connected across the contacts of said switch unit in series with said electrical connector whereby the said source is energized when the incandescent bulb is de-energized and the socket is illuminated when de-energized for visibility in the dark, said source comprising a glow lamp having spaced electrodes and provided with a series resistance across said switch unit, said glow lamp being secured to said switch unit by a plastic member embracing the glow lamp and having flanges secured to the switch unit.

2. In an illuminated electrical switch socket, the combination of a housing member with a switch unit in said housing member and an electrical connector carried by said housing member for receiving an incandescent bulb, said switch unit controlling the line connection to said electrical connector, a source of illumination located inside said housing and visible on the outside of said housing, said source being connected across the contacts of said switch unit in series with said electrical connector whereby the said source is energized when the incandescent bulb is de-energized and the socket is illuminated when de-energized for visibility in the dark, said housing comprising a tubular member for housing a switch unit and connector, and a cap member, said cap being provided with a plurality of window openings adjacent said source.

3. In an illuminated electrical switch socket, the combination of a housing member with a switch unit in said housing member and an electrical connector carried by said housing member for receiving an incandescent bulb, said switch unit controlling the line connection to said electrical connector, a source of illumination located inside said housing and visible on the outside

8 of said housing, said source being connected across the contacts of said switch unit in series with said electrical connector whereby the said source is energized when the incandescent bulb is de-energized and the socket is illuminated when de-energized for visibility in the dark, said housing comprising a tubular member for housing a switch unit and connector, a cap member, said cap being provided with a plurality of window openings adjacent said source, and a dome of translucent plastic of predetermined color located under said cap to close said window openings.

4. In an illuminated electrical switch socket, the combination of a housing member with a switch unit in said housing member and an electrical connector carried by said housing member for receiving an incandescent bulb, said switch unit controlling the line connection to said electrical connector, a source of illumination located inside said housing and visible on the outside of said housing, said source being connected across the contacts of said switch unit in series with said electrical connector whereby the said source is energized when the incandescent bulb is de-energized and the socket is illuminated when de-energized for visibility in the dark, said housing comprising a tubular member for housing a switch unit and connector, a cap member, said cap being provided with a plurality of window openings adjacent said source, a dome of translucent plastic of predetermined color located under said cap to close said window openings, said cap and dome both having radial securing flanges, and a screw sleeve engaging the threads on said tubular member and clamping said securing flanges against the end of the tubular member.

5. In an illuminated electrical switch socket, the combination of a housing member with a switch unit in said housing member and an electrical connector carried by said housing member for receiving an incandescent bulb, said switch unit controlling the line connection to said electrical connector, and a source of illumination located inside said housing and visible on the outside of said housing, said source being connected across the contacts of said switch unit in series with said electrical connector whereby the said source is energized when the incandescent bulb is de-energized and the socket is illuminated when de-energized for visibility in the dark, said source comprising a glow lamp having spaced electrodes and provided with a series resistance across said switch unit, said glow lamp being enclosed with said switch unit in said housing by a translucent member enclosing the glow lamp and secured to said housing.

6. In an illuminated electrical switch socket, the combination of a housing member with a switch unit in said housing member and an electrical connector carried by said housing member for receiving an incandescent bulb, said switch unit controlling the line connection to said electrical connector, a source of illumination located inside said housing and visible on the outside of said housing, said source being connected across the contacts of said switch unit in series with said electrical connector whereby the said source is energized when the incandescent bulb is de-energized and the socket is illuminated when de-energized for visibility in the dark, said housing comprising a tubular member for housing a switch unit and connector, and a cap member, at least a portion of said cap being light-pervious 75 for transmitting illumination from said source

of illumination to facilitate the finding of said socket in the dark when the incandescent bulb is turned off.

7. In an illuminated electrical switch socket, the combination of a housing member with a switch unit in said housing member and an electrical connector carried by said housing member for receiving an incandescent bulb, said switch unit controlling the line connection to said electrical connector, and a source of illumination located inside said housing and visible on the outside of said housing, said source being connected across the contacts of said switch unit in series with said electrical connector whereby the said source is energized when the incandescent bulb is de-energized and the socket is illuminated when de-energized for visibility in the dark, said source comprising a glow lamp having spaced electrodes and provided with a series resistance across said switch unit, said glow lamp being secured to said switch unit by a complementary plastic member embracing the glow lamp and having flanges secured to the switch unit, said switch unit including an insulating support, and said support being provided with an elongated recess for receiving said series resistance. 25

8. In an illuminated electrical switch socket, the combination of a housing member with a switch unit in said housing member and an electrical connector carried by said housing member for receiving an incandescent bulb, said switch unit controlling the line connection to said electrical connector, and a source of illumination located inside said housing and visible on the outside of said housing, said source being connected across the contacts of said switch unit in series with said electrical connector whereby the 30

said source is energized when the incandescent bulb is de-energized and the socket is illuminated when de-energized for visibility in the dark, said source comprising a glow lamp having spaced electrodes and provided with a series resistance across said switch unit, said glow lamp being secured to said switch unit by a complementary plastic member embracing the glow lamp and having flanges secured to the switch unit, the said housing comprising a cylindrical insulating member surrounding the switch unit and the connector, and a cap engaging the end of said cylindrical member and having a central aperture for passing conductors, said cap being constructed of translucent material, and a threaded member for securing said cap and cylindrical member together. 15

9. An illuminated electrical switch socket according to claim 6, in which the cap is opaque and is provided with a light transmitting window. 20

10. An illuminated electrical switch socket according to claim 6, in which the cap is constructed of translucent moldable plastic. 25
